UNITED STATES PATENT OFFICE.

HERBERT G. UNDERWOOD, OF NEW YORK, N. Y.

INTERNAL-COMBUSTION ENGINE.

No. 846,070.

Specification of Letters Patent.

Patented March 5, 1907.

Application filed June 7, 1905. Serial No. 264,042.

To all whom it may concern:

Be it known that I, HERBERT G. UNDERWOOD, a citizen of the United States, residing in West New Brighton, borough of Richmond, of the city of New York, in the State of New York, have invented certain new and useful Improvements in Internal-Combustion Engines, of which the following is a specification, reference being had to the accompanying drawings, forming a part hereof.

This invention relates particularly to internal-combustion engines of the two-cycle type, in which a fresh charge is compressed at every backward stroke of the piston and is exploded at every forward stroke.

The object of the invention is in general to improve the construction and increase the efficiency of engines of this type.

The features and details of improvement will be more particularly described hereinafter with reference to the accompanying drawings, in which the invention is illustrated as embodied as to its several features in convenient and practical form.

In said drawings, Figure 1 is a view in front elevation of an internal-combustion engine having the present improvements applied thereto. Fig. 2 is a view thereof in side elevation, the shaft being shown in section.

Fig. 3 is a view in vertical section on the plane indicated by the line 3 3 of Fig. 1. Fig. 4 is a view, partly in section, on the horizontal plane indicated by the line 4 4 of Fig. 2. Fig. 5 is a detail view, on an enlarged scale, of a portion of the governor mechanism. Fig. 6 is a top view of the cylinder-head. Fig. 7 shows a portion of the igniter in side and edge views. Fig. 8 is a partial view in elevation from the opposite side of the engine to that shown in Fig. 2. Fig. 9 is a view in vertical section on the plane indicated by the line 9 9 of Fig. 8. Fig. 10 is a view in horizontal section on the plane indicated by the line 10 10 of Fig. 8.

In the engine represented in the drawings the working cylinder *a*, suitably jacketed, as at *a'*, is set vertically and is suitably supported, as by struts *b*, upon a base-plate *b'*, to which are secured the bearings *b''* for the

crank-shaft *c*. It will be obvious that the cranks are not inclosed and that the cylinder-head hereinafter more particularly referred to is at that end of the cylinder which is nearest to the crank-shaft *c*. The cranks *c'*, of which there are two, are connected by

pitmen *c''* with a wrist-pin *d*, the ends of which project from the upwardly-extended cylindrical trunk-piston *d'* through slots *a''*, one of which is shown in dotted lines in Fig. 2 in the upward extension *a''* of the cylinder *a*. As will be observed by reference to Fig. 3, the trunk-piston *d'* when in its highest position extends nearly to the head *a'''* of the cylinder extension *a''*, its length being greater than its stroke, so that the slots *a''* in the cylinder-wall are always covered by the trunk-piston. The piston *d'* is provided near its forward or head end with a port *d''*, which is adapted to register as the piston approaches the limit of its forward stroke with a port *a''* in the cylinder-wall. The latter communicates with a chamber *a''*, in which the air is mixed with the fuel basis of the explosive charge, and the latter communicates with the head end of the cylinder—that is, with the working cylinder—through a port *a''*, which is likewise uncovered by the piston as it approaches the limit of its upward or forward stroke. An exhaust-port *a''* is also provided in the wall of the working cylinder to be uncovered by the piston as it approaches the limit of its forward stroke. In the wall of the cylinder extension *a''* are also provided air-inlet ports *a''* in such position as to be uncovered by the piston as the latter approaches the limit of its downward or rearward stroke. With this construction the air admitted through the ports *a''* is compressed during the forward movement of the piston and is admitted to the working cylinder as the piston completes its forward stroke. As it passes practically through the entire length of the trunk-piston and close to the head end thereof the latter is kept properly cool. Furthermore, as the rearward movement of the piston during its compression-stroke is in a downward direction, the weight of the piston and connected parts is taken advantage of to assist in the compression of the charge which is admitted with the air into the working cylinder through the ports described. The exhaust takes place at the end of the forward stroke of the piston, as usual in engines of this type.

Before describing the devices which control the formation and admission to the working cylinder of the explosive charge and the devices for igniting the same the devices provided for starting the engines from a condition of rest will be explained, it being un-

derstood that the explosive mixture is formed in the chamber a^5 and is delivered therefrom through the port a^6 into the working cylinder.

For the starting of the engine from a condition of rest there is provided a suitable reservoir for compressed air, which is sufficiently indicated by the pipe e , which conducts the compressed air from the reservoir to the air-compressing end of the cylinder a^3 , the admission of the air being controlled, primarily, by a hand-operated valve e' . From the pipe e the air is admitted to the extreme forward or upper end of the cylinder a^3 through a valve which can be thrown out of operation altogether or can be operated from the moving parts of the engine to admit the compressed air at the proper time to produce a rearward or downward movement of the piston and to cut off the supply of air at the proper time. As shown in the drawings, the valve provided for the purpose is a slide-valve f , having a port f^2 , adapted to register with a port f^2 at the head or upper end of the air-compression cylinder. This valve may be operated, as shown in the drawings, by a lever g , suitably pivoted, as at g' , upon the cylinder-wall and acted upon by a spring g^2 to draw the port f^2 to the right of the port f^2 , and thereby prevent the admission of air from the source of supply. The lever is provided with a foot g^3 in such a position as to be acted upon by a roller c^3 on one of the pitmen c^2 . A locking-pin g^4 is carried by the lever g and adapted to enter a recess g^5 in the cylinder-casting to hold the lever against the pressure of the spring g^2 , with the port f^2 in the slide-valve at the left of the port f^2 in the cylinder-wall for the purpose of cutting off the admission of air from the reservoir after the engine has started or when it is not in operation. It will be seen that if the engine is at rest, with the piston d' in its highest position, as represented in Fig. 3, and the hand-valve e' is opened the valve f is also opened at the same time, and air admitted from the reservoir rushes through the port d^2 and the mixing-chamber a^5 , carrying a charge into the working cylinder. At the same time, the engine being moved slightly off center, the air-pressure drives the piston downward and continues to drive it downward until the valve f is permitted to close, and thereafter during expansion until the ports a^8 are opened, the latter becoming exhaust-valves as to the air admitted from the reservoir. During such movement of the piston the charge in the working cylinder is compressed and being ignited at the proper time drives the piston forward. As soon as the regular operation of the engine is established the valve e' is closed and the lever g is locked in its inoperative position by the pin g^4 . Should it happen that the engine is stopped off center, so that the ports d^2 and a^4 do not register, then no charge will be driven into the work-

ing cylinder during the first downward movement of the piston, and the piston being then returned by the momentum of the parts, aided by the expansion of the air in the working cylinder a second downward movement 70 of the piston must be effected by the compressed air before the regular operation of the engine is established.

In the engine represented in the drawings the fuel basis of the explosive mixture is supplied from any suitable source through a pipe h , which is provided with a nozzle and valve-chamber h' within the mixing-chamber a^5 . The extremity of the pipe is provided with an inwardly-opening valve h^2 , which is held 80 normally to its seat by a spring h^3 . The stem of the valve h^2 projects beyond the extremity of the pipe h' into the path of an arm i , by which the valve is opened to permit the escape of the proper quantity of fluid to form 85 the basis of the explosive mixture. The arm i is secured to a shaft i' , which is extended through the wall of the mixing-chamber a^5 and is provided exteriorly with an arm i^2 , adapted to be acted upon by some moving 90 part of the engine to open the valve h^2 at the proper instant. In the engine shown the valve is operated by a mechanism which is dependent upon the speed of the engine or, in other words, by governor devices. As 95 shown particularly in Figs. 2 and 4, an arm k , pivoted, as at k' , upon a suitable bracket, is connected by a link k^2 with one of the pitmen c^2 , so that it is swung up and down as the piston reciprocates. Upon the lever k is pivoted a pendulum-arm l , which is pressed normally in one direction by a spring k^3 , adjustably supported, through a screw k^4 , upon an arm k^5 of the lever k . The pendulum is provided with a finger l' , which in the normal 100 operation of the engine overlies the extension of the arm i^2 on the shaft i' , so that as the lever k is swung up and down the shaft i' is oscillated and the valve h^2 is opened at every movement. If, however, the engine 105 is operating at a speed higher than the normal, then the pendulum-arm l assumes such a position relative to the shaft i' that the finger l' thereof fails to engage the arm i^2 , and the valve h^2 therefore is not opened to admit 110 more fluid. It may be desirable not only to prevent the admission of fuel when the engine is running too fast, but to prevent also the admission 115 to the working cylinder of whatever mixture there may be in the mixing-chamber a^5 and even of additional air. For this purpose there is provided a butterfly-valve m , mounted within the mixing-chamber a^5 upon a shaft m' , which carries outside of the mixing-chamber a triangular block m^2 . A flat 120 spring m^3 is secured to the supporting-bracket to coöperate with the block m^2 and maintain the valve in one position or the other, as the case may be. The block m^2 is 125

130

also provided with lugs m^4 and m^5 , which are arranged to coöperate with a finger l^2 , also carried by the pendulum l . Normally the valve m stands in the position represented in full lines in Figs. 3 and 5, leaving the passage unobstructed; but if the engine runs too fast and the admission of fuel is cut off by the action of the pendulum l then at the same time the finger l^2 of the pendulum swings into position to strike the lug m^5 on the block m^2 , rocking the shaft and the valve m into the position of the latter, indicated by dotted lines, in which it prevents the passage of air or vapor through the mixing-chamber. As soon as the engine resumes normal speed then the finger l^2 strikes the lug m^4 of the block m^2 and restores the valve to its operative position.

For the ignition of the charge in the explosion-chamber use is made of the property possessed by certain bodies, notably, finely-divided platinum, of effecting the ignition of the gases to which they are exposed. Ordinarily these bodies lose the property referred to after use for a considerable time from causes which are not necessary to be more particularly referred to herein; but it has been found in the development of the present invention that under the conditions to which said bodies are exposed in the operation of internal-combustion engines the desired quality is retained unimpaired, particularly if the bodies are so placed as to prevent the accumulation of carbon thereon. In the application of this feature of the invention the gas-occluding body, preferably platinum in suitable form, is preferably distributed in the cylinder-head in the form of points n and thin strips n' , which are suitably supported. As shown in Figs. 3, 6, and 7 of the drawings, these points n and strips n' are secured to blocks n^2 , which are mounted in the cylinder-head o , and are preferably secured therein by a bolt or rod o' . It is found that the distribution of gas-occluding material at different points in the cylinder-head secures, under the influence of the compression of the gaseous charge in contact with the occluding material, certainty of operation, so that ignition takes place without fail whenever a proper mixture of the gaseous material is compressed in the working cylinder. Furthermore, through the support of the occluding material at some distance from the extremity of the cylinder-head and perhaps the action of the explosion, the occluding material is kept clear and free from carbon and retains its peculiar property for a long time in actual use.

The occluding material, arranged substantially as described, may be relied upon to effect the ignition during the operation of the engine; but in case it should be desired to warm up the engine when it has been at rest for a sufficient length of time to permit the

parts to become cooled there may also be provided a torch-igniter, and for this purpose the cylinder-head may be formed with a cylindrical guard-tube o^2 , provided at one end with a burner o^3 , and having projected into it from the explosion-chamber one or more tubular igniters o^4 , which preferably have their mouths covered with platinum-gauze, as at o^5 . This torch-igniter is employed and operates substantially in the manner common to other engines of the type of that shown and described herein.

It will be understood that various changes may be made in the details of construction and arrangement of parts and that the invention is not to be limited to the precise construction and arrangement shown and described herein.

I claim as my invention—

1. In an internal-combustion engine, the combination of a working cylinder having an upward extension with opposite longitudinal slots and closed ends, an uninclosed crank-shaft, a trunk-piston open from its head to its end and covering the slots in the cylinder, a wrist-pin extended from the piston through said slots and pitmen connecting the wrist-pin and the crank-shaft external to the cylinder, the working cylinder being above the crank-shaft with its head end adjacent to the crank-shaft, substantially as described.

2. In an internal-combustion engine, the combination of a base-plate, an uninclosed crank-shaft having bearings therein, a working cylinder supported above said base-plate with its head end above the crank-shaft and provided with an upward extension having opposite longitudinal slots and closed ends, a trunk-piston open from its head to its end and arranged to cover said slots, a wrist-pin extended from the piston through said slots, and pitmen connecting the wrist-pin and the crank-shaft external to the cylinder, substantially as described.

3. In an internal-combustion engine, the combination of a cylinder having a closed head and a closed extension with opposite slots and provided with an inlet-port adapted to be uncovered by the piston as it approaches the forward limit of its stroke, a second port connected with the first, and a third port in said extension adapted to be uncovered by the piston as it approaches the rearward limit of its stroke, a hollow trunk-piston adapted to receive through its open end air admitted through the last-named port and provided near its head end with a port arranged to register with the second-named port as the piston approaches the forward limit of its stroke, an uninclosed crank-shaft, a wrist-pin projecting from the piston through said slots and external pitmen connecting the wrist-pin and the crank-shaft, substantially as described.

4. In an internal-combustion engine, the

- combination of an uninclosed crank-shaft, a cylinder above the crank-shaft having its closed head end adjacent to the crank-shaft, having a closed extension remote from the crank-shaft with opposite longitudinal slots, and provided with an inlet-port adapted to be uncovered by the piston as it approaches the forward limit of its stroke, a second port connected with the first, and a third port in said extension adapted to be uncovered by the piston as it approaches the rearward movement of its stroke, a hollow trunk-piston adapted to receive through its open end air admitted through the last-named port and provided near its head end with a port arranged to register with the second - named port as the piston approaches the forward limit of its stroke, a wrist-pin projecting from the piston through said slots, and external pitmen connecting the wrist-pin and the crank-shaft, substantially as described.
5. In an internal-combustion engine, the combination of a cylinder having a closed head and a closed extension with opposite longitudinal slots, and provided with an inlet-port adapted to be uncovered by the piston as it approaches the forward limit of its stroke, a second port connected with the first through a mixing-chamber and a third port in said extension adapted to be uncovered by the piston as it approaches the rearward limit of its stroke, means to supply the fuel basis of the charge to said mixing-chamber, a hollow trunk-piston adapted to receive through its open end air admitted through the last-named port and provided near its head end with a port arranged to register with the second-named port as the piston approaches the forward limit of its stroke, an uninclosed crank-shaft, a wrist-pin projecting from the piston through said slots, and external pitmen connecting the wrist-pin with the crank-shaft, substantially as described.
6. In an internal-combustion engine, the combination of an uninclosed crank-shaft, a working cylinder having its closed head end adjacent to the crank-shaft and having an opposite closed extension with opposite longitudinal slots, a piston covering said slots, a wrist-pin projecting from the piston through said slots, external pitmen connecting the wrist-pin and the crank-shaft, and means to admit air under pressure to said extension in front of the piston, substantially as described.
7. In an internal-combustion engine, the combination of an uninclosed crank-shaft, a working cylinder having its closed head end adjacent to the crank-shaft and having an opposite closed extension with opposite longitudinal slots, a piston covering said slots, a wrist-pin projecting from the piston through said slots, external pitmen connecting the wrist-pin and the crank-shaft, means to admit air under pressure to said extension in front of the piston, and means actuated by a moving part of the engine to control the admission of air to said extension, substantially as described.
8. In an internal-combustion engine, the combination of an uninclosed crank-shaft, a working cylinder having its closed head end adjacent to the crank-shaft and having an opposite closed extension, with opposite longitudinal slots, a piston covering said slots, a wrist-pin projecting from the piston through said slots, external pitmen connecting the wrist-pin and the crank-shaft, means to admit air under pressure to said extension in front of the piston, a valve to control the admission of air, and means actuated by a moving part of the engine to operate said valve, substantially as described.
9. In an internal-combustion engine, the combination of an uninclosed crank-shaft, a working cylinder having its closed head end adjacent to the crank-shaft and having an opposite closed extension, with opposite longitudinal slots, a piston covering said slots, a wrist-pin projecting from the piston through said slots, external pitmen connecting the wrist-pin and the crank-shaft, means to admit air under pressure to said extension in front of the piston, a valve to control the admission of air, means actuated by a moving part of the engine to operate said valve, and means to retain said valve normally in a closed position, substantially as described.
